SANDWICH TOAST PRESS

Evelyn F. Trovinger, 1425 Lake St.,
Lodi, Calif. 95240

Filed Apr. 17, 1973, Ser. No. 351,856

Term of patent 14 years

Int. Cl. D7—02

U.S. Cl. D7—99

FIG. 1 is a side elevational view of a sandwich toast press showing my new design in open position;

FIG. 2 is a bottom plan view thereof;

FIG. 3 is a side elevational view thereof in closed position;

FIG. 4 is a top plan view of FIG. 3;

FIG. 5 is a left end elevational view of FIG. 3; and FIG. 6 is a right end elevation of FIG. 3.

I claim:

The ornamental design for a sandwich toast press, as shown.
